(57) **CLAIM**

The ornamental design for over-ear headphones, as shown
and described.

DESCRIPTION

FIG. 1 is a front, top, and left perspective view of over-ear
headphones showing my new design;

FIG. 2 is rear, bottom, and right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded areas
represent the bounds of the claimed design, the dash dash
broken lines represent the bounds and unclaimed portions of
the over ear headphone headband, and all other broken lines
depict portions of the over-ear headphones that form no part
of the claimed design.
